KALEIDOSCOPIC DEVICE

Wilhelm Schmidt, Berlin-Schmargendorf, Germany, assignor to Erika Annemarie Mulert, New York, N. Y.

Application March 26, 1938, Serial No. 198,244

5 Claims.

(Cl. 40—77)

This invention relates to kaleidoscopes and the like and more particularly to a device of this character in which the kaleidoscopic principle has been applied to bring into view, successively, images or optical illusions of various objects and displays and held for periods of sufficient duration to enable an observer to perceive the same.

The fundamental principles of the invention have been described and illustrated in my application Serial Number 66,479, filed February 29, 1936. This application is a continuation in part thereof and contemplates certain improvements thereover.

The principal object is to provide a device or apparatus of the character indicated and described in said aforementioned application having a simplified and more efficient mechanism for changing the images or illusions during the course of rotation of the pattern or patterns.

Another object of the invention is to provide a kaleidoscopic apparatus by which a series of successive or progressive images or illusions may be produced to give the appearance of an animated or moving object or objects.

Still a further object is to provide a switching mechanism for an apparatus of the character indicated of simple, efficient and inexpensive construction by means of which the various patterns or displays may be successively illuminated.

Other objects and advantages will become apparent as the specification proceeds and when considered in connection with the accompanying drawings which illustrate the preferred embodiment of the improvement. It will be understood that this disclosure is made without limitation to the specific details shown therein and adaptations may be made within the scope of the appended claims.

In the drawings:

Figure 1 is a perspective view of the apparatus embodying the invention showing one pattern or display mounted thereon.

Figure 2 is a section along the line 2—2 of Figure 1.

Figure 3 is a plan view of the camming or switching mechanism according to the invention.

Figure 4 is a section along the line 4—4 of Figure 3.

Figure 5 is a view taken along the line 5—5 of Figure 3, and

Figure 6 is a section taken along the line 6—6 of Figure 2.

As indicated the apparatus operates on the principle that images passing successively before the eye at the speed of fifteen or more a second

will appear as moving or if the successive images are identical, the observer will receive the impression of a stationary picture or object.

Referring in more detail to the drawings, the reference character 10 indicates generally the apparatus having mounted thereon for projection or exposure a pattern or display 11. The apparatus comprises outwardly a base plate 12, provided with legs 12a, a cover plate 13, a rotary plate or disc 14, having mounted thereon a housing 15, the latter terminating in a vertical support frame 16 for holding the various patterns or displays 11.

The disc 14 is rotated by belt 17 which is driven by a motor covered by the housing 18.

The base plate 12 is provided with a central cap or recess 19 from which extends the stationary shaft member 20 which has mounted thereon the socket 21 and the electric light bulb 22.

The cover plate is spaced from the base plate 12 by means of the peripheral vertical wall 23 so as to provide room for the lead cord 22a and held firmly in position on the base plate by means of bolts 24 and washer 25. The cover plate is recessed at 26 and 27 to accommodate respectively the drive portion 28 and the hub 29 which are formed integrally with the disc 14.

From the recess 27 of the cover plate extends the tubular stationary shaft 30, which at its upper end is threaded, the purpose of which will hereinafter be described.

The hub 29 is rotatable about the shaft 30 and a bushing 31 and a sweat ring 32 may be interposed to reduce the friction. This bushing and sweat ring may, of course, be substituted for by other bearings offering less friction such as ball bearings or thrust bearings.

The disc 33 is fixedly mounted on the disc 14 for rotation therewith. The bottom surface of the disc 33 is provided with brackets 35 in which the shaft 36 is rotatably supported. The shaft 36 in turn carries the pinion 37 (see Fig. 5) which engages the threads of the stationary shaft 30. Thus upon rotation of the disc 33 the pinion 37 will be turned the space of one tooth for each revolution. The stepwise rotation is transmitted to the pinion 38 by the worm 39 which is also mounted on shaft 36. The pinion 38 is mounted on the shaft 40 of the cam mechanism 41 and thus the latter is rotated in a similar manner.

The cam mechanism 41 comprises a circular disc 42 having a cam pin 43, the purpose of which will hereinafter be described, and a superimposed crescent disc 44. The periphery of the latter frictionally engages the concentric periphery of 51

the arms 46 of the switch plate 45 which has the shape of a Maltese cross. Thus the crescent disc 44 will form a clutch for the switch plate 45 so that the latter will be rotated together with the 5 disc 33 and the frame 16. The arms 46 are separated by the slots 47.

The switch plate 45 is formed integral with the disc 48 which is mounted on the collar 49 of the disc 33. Because of the frictional engagement between the concentric arcs of the crescent disc 44 and the arms 46, the switch plate 45 as well as the disc 48 will be rotated together with the disc 33 and the drive 14.

The opaque shield 50 is removably mounted on 15 the disc 48 by means of a conventional pin and slot arrangement and is rotated therewith. The shield 50 is provided with a slot or window 51 through which the light may be projected on one of the patterns or displays.

20 The arms 46 of the switch plate 45 are arranged to correspond with window 51 and the displays 11. Thus when the cam mechanism and the switch plate 45 are in engagement as shown in Figure 3, the window will be directly 25 in front of one of the displays. The cam mechanism and the switch plate are also so calibrated that the pin 43 is moved the space equal to the space between each slot 47 with each step. The recess 52 of the crescent disc 44 is also so arranged 30 that the arm 46 and the disc 44 will be freed from engagement when the pin 43 engages one of the slots 47. Thus after the pin 43 has entered into the slot 47 it will turn the switch plate together with the shield 50 the space of one arm 35 with the next step, so that the window 51 will be directly in front of the succeeding pattern. On the next step of the cam disc 41, and as the pin disengages the slot 47, the concentric arcs of the disc 41 and the arm will again come into frictional contact, so that the disc 33 together 40 with the shield will again be rotated with the drive 14 and the display support 16.

The individual displays or patterns are preferably of the type described in my co-pending application Serial Number 198,245, filed March 26, 45 1938. They are preferably hollow, having side walls and an outer wall on which transparent areas are arranged according to the design or display the image of which is desired to be produced. They are slid into the channels 53 of the 50 vertical frame 16 as shown in Figure 1 with the open end facing the shield. It will be understood that the space between the channels corresponds to the stepwise movement of the shield 55 50, the switch plate 45 and the cam mechanism so that the window 51 will always be directly in line with the open end of the hollow display 11. The transparent areas will thus be illuminated and when the display is rotated it will produce 60 a steady image of the object for which the display has been designed. The display usually does not include more than one-half of the object the image of which is to be produced, so that one-half will appear on each side of the frame 16 when it is rotated.

65 The displays may also include various advertising matter, as explained in my co-pending application Serial Number 198,245, filed Mar. 26, 1938. Thus the rotation of the illuminated display will not only produce a three dimensional 70 image of the object to be advertised but also the desired advertising matter will appear therein.

In order to make the apparatus more steady, 75 the shield 50 may be resiliently pivoted within

the frame 16 by means of the pivot 53 and the spring 54, and a counterweight 55 on the disc 33 may be provided to offset the effect of the cam mechanism when the disc is rotated.

The purposes to which the device lends itself 5 are numerous. Thus the displays may be selected to portray various sequences in the advertising scheme and take the place of the conventional cinematographic apparatus used for projecting motion pictures. It may also be used as 10 a toy or as a decorative article in the home. The apparatus may be easily hooked up to any double wall plug by means of the cord 22a and the cord 22b, the former for the light and the latter for the motor. The light as well as the motor 15 may, of course, also be controlled from a single switch.

It will also be understood that the motor may also be arranged directly under the foot plate 20 to drive the disc 14 directly and various other 25 modifications may be made within the scope of the following claims. It will also be clear that instead of moving the shield, the switch mechanism may be employed to switch on successively 25 separate lamps for illuminating the various patterns, without departing from the scope of the invention.

What is claimed is:

1. A kaleidoscopic device of the character described comprising a rotatable frame and means 30 for rotating the same, a plurality of displays having transparent areas according to the image to be produced supported on said frame and rotatable therewith, a stationary light source mounted within said frame, movable means for confining 35 the light to a single one of said displays, and clutch means controlled by the rotation of said frame to move said light confining means stepwise with respect to said frame to illuminate successively said displays. 40

2. A kaleidoscopic device of the character described comprising a rotatable frame and means for rotating the same, a plurality of different displays having transparent areas according to the image to be produced supported on said frame 45 and rotatable therewith, a stationary light source mounted within said frame, a shield about said light source and movable relative thereto having a window for confining the illumination to a single one of said displays, a switch plate carried by said shield, and means normally forming 50 a clutch between said frame and said shield carried by said frame and controlled by the rotation thereof for actuating said switch plate at predetermined intervals of time to move said shield stepwise with respect to said frame to illuminate successively said displays. 55

3. A kaleidoscopic apparatus of the character described comprising a rotatable frame and means for rotating the same, a plurality of different displays supported on said frame and rotatable therewith, means within said frame for illuminating said displays, a shield about said light means and movable relative thereto having a window for confining the illumination to a single one of said displays, a switch member carried by said shield, a clutch mechanism carried by 60 said frame normally engaging said switch member and means carried by said clutch mechanism and controlled by the rotation of said frame for releasing said engagement and actuating said switch member to move said shield stepwise with respect to said frame at predetermined intervals whereby said displays will be successively illuminated during the rotation thereof. 65 70 75

4. A kaleidoscopic apparatus of the character described comprising a rotatable frame and means for rotating the same, a plurality of different displays supported on said frame and rotatable therewith, means within said frame for illuminating said displays, a shield about said light means and movable relative thereto having a window for confining the illumination to a single one of said displays, a slotted switch member carried by said shield, an individually rotatable clutch mechanism carried by said frame and controlled by the rotation thereof normally engaging said switch member, cam means carried by said clutch mechanism for engaging said slotted switch member on each revolution of said clutch member, and separate means on said clutch member for releasing the engagement thereof with said switch member when said cam means engages the same, whereby said shield will be moved stepwise with respect to said frame on each revolution of said clutch mechanism to illuminate successively said displays.

5. A kaleidoscopic apparatus of the character described comprising a rotatable frame and

means for rotating the same, a plurality of different displays supported on said frame and rotatable therewith, means within said frame for illuminating said displays, a shield about said light means and movable relative thereto having a window for confining the illumination to a single one of said displays, a switch plate carried by said shield having the configuration of a Maltese cross the arms of which terminate in an inverted circular arc, an individually rotatable clutch mechanism carried by said frame and controlled by the rotation thereof having a crescent shaped disc the periphery of which is concentric with and normally engages the circular arc of said arms whereby said shield will be rotated together with said frame, a pin member opposite the cut-out portion of said crescent and mounted on said clutch mechanism for engagement on each revolution thereof with the slots between the arms of said Maltese cross plate whereby said shield will be unclutched and moved stepwise with respect to said frame to illuminate said displays successively.

WILHELM SCHMIDT.
